UNITED STATES PATENT OFFICE.

GORDON E. KENT AND FRED W. YUTZLER, OF ROME, NEW YORK, ASSIGNEES TO THE KENT COMPANY, INC., OF ROME, NEW YORK, A CORPORATION OF NEW YORK.

VACUUM CLEANING TOOL.

Application filed August 30, 1924. Serial No. 735,092.

This invention relates to vacuum cleaning apparatus and more particularly to tools adapted to be attached to the end of a flexible hose for removing dust from different articles.

The invention has particular reference to vacuum cleaning tools adapted for use in stores for cleaning the merchandise and particularly articles that would ordinarily be picked up by the suction in the cleaning tools.

Much difficulty has been experienced in attempting to use ordinary cleaning tools for cleaning small articles of merchandise such as are commonly found in five and ten-cent stores, because the suction either draws the articles into the apparatus or they tend to clog the opening through which air is drawn into the tool. It is one of the objects of this invention, therefore, to overcome this difficulty and provide a tool especially adapted for cleaning small articles of merchandise.

A further object of the invention is to provide a tool of comparatively simple construction that will be convenient and efficient in operation and adapted for rapid work.

Other objects of the invention and the features of novelty will be apparent from the following description, taken in connection with the accompanying drawings, of which:

Figure 1 is a longitudinal section through a vacuum cleaning tool embodying our invention, the tool being shown in connection with the representation of the hand of the operator, and a tray of merchandise.

Fig. 2 is an end elevation of the tool shown in Fig. 1;

Fig. 3 is a fragmentary side elevation of the same tool, parts being shown in section and the valve being in a different position from that shown in Fig. 1;

Fig. 4 is a section on the line 4—4 of Fig. 3;

Fig. 5 is a side elevation of another form of tool embodying my invention; and

Fig. 6 is a longitudinal section of the same shown in connection with a cleaning nozzle.

Referring to the drawings, 10 indicates a tubular casing, preferably of rectangular cross-section having openings at its upper and lower ends, the upper end being preferably cut on a diagonal to the axis of the casing, as indicated at 11. The lower end of the casing is provided with a screen 12 which

may have meshes about one-sixteenth of an inch square, although the size of the meshes will be determined by the size of the articles to be cleaned, it being the purpose of the screen to prevent the articles, that are being cleaned, from being drawn into the casing.

A tubular extension 13 is secured to one side of the casing 10 and preferably projects into the casing a short distance, as indicated at 14. The extension 13 is preferably of circular form and adapted to be connected to a hose 15 which forms a part of the vacuum-producing apparatus. The extension 13 also serves as a handle for the tool permitting it to be gripped by the hand of the operator, as indicated in Fig. 1. A valve 16 is arranged in the upper part of the casing 10, having small ears 17 on opposite sides by means of which it is pivoted or hinged in the casing, a pivot being indicated at 18. The upper end of the valve 16 has a curved extension 19 which projects through the opening in the upper end of the casing 10 and is adapted to be engaged by the thumb of the operator for the purpose of actuating the valve, as indicated in Fig. 1.

The valve 16 is preferably made of a piece of flat metal and is adapted to swing from the position shown in Fig. 1, where it closes the opening at the upper end of the casing, to the position shown in Fig. 3, where it seals the end of the extension 13.

In the operation of the tool shown in Figs. 1 to 4 the screened lower end of the casing 10 is moved over the articles to be cleaned, the operator pressing on the handle 19 of the valve to hold it in the position shown in Fig. 1 which permits air to be drawn through the screened lower end of the tool and discharged through the extension 13 to the vacuum-producing apparatus. A tray for merchandise is indicated at 20 in Fig. 1 and at 21 we have indicated small articles of merchandise such as screws, bolts or other small articles commonly found in a five and ten-cent store. The suction tends to pick up small articles and they are prevented, by the screen 12, from passing through the casing 10 and into the vacuum-producing apparatus. When the tool has been moved over the articles in a tray, some of the articles will be found to adhere to the screen 12, and, in order to release these articles and prevent them from being mixed with articles of a different kind in another tray, we have pro-

vided the valve 16. When the cleaning of any particular tray has been finished, the operator lifts his thumb from the handle 19, thereby permitting the valve 16 to swing 5 to the closed position, shown in Fig. 3, which shuts off the extension 13 from the casing 10 and relieves the interior of the casing from the suction action of the vacuum-producing apparatus. The closing of the valve 16 is 10 effected by the suction within the casing and the fact that flow of air through the screen 12 is very much restricted by the articles being cleaned, so that the atmospheric pressure will move the valve away from the position shown in Fig. 1 and the current of air 15 thereby admitted through the opening 11 will carry the valve to the closed position. This will release the articles from the screen 20 12 and permit them to drop back into the tray in which they belong. The tool is then moved to another tray and the operator presses on the handle 10 to return the valve 16 to the position shown in Fig. 1 which again opens the interior of the casing 10 to 25 the suction action and causes air to flow through the screened lower end of the casing.

We have found that it is frequently desirable to have various forms of cleaning nozzles to suit the requirements for cleaning 30 different kinds of merchandise and in order to have our invention meet this condition we have illustrated a modification of the invention in Figs. 5 and 6. In this form of 35 the invention there is a casing 22, preferably of rectangular cross-section and having on opposite sides extensions 23 and 24. One of the other sides has an opening indicated at 25, the wall 26 on this side of the casing being preferably deflected inwardly 40 as shown in Fig. 6. The extensions 23 and 24 are rigidly secured to the casing by soldering or in any other suitable manner and preferably extend a short distance into the casing in the same manner as the extension 45 13 in the form of the invention first described. At 27 we have indicated a cleaning nozzle which has a telescopic connection with the extension 24. It will be understood that the nozzle indicated at 27 may represent 50 any one of a variety of shapes of nozzles, each of which is especially adapted for cleaning a particular class of merchandise but all of such nozzles will have their open end, which is moved over the articles to be 55 cleaned, provided with some form of screen such as indicated at 28.

In order to secure the nozzle 27 in the extension 24 we provide a special form of locking device which consists of a bead 29 in the 60 extension 24 and a curved spring 30 arranged on the inside of the end of the nozzle 28 and having a projection 31 on one side which extends through an opening 32 in the wall of the nozzle, for cooperation with the 65 interior of the bead 29. This form of se-

curing means normally holds the parts together but permits them to be readily separated when desired.

Within the casing 22 there is a valve 33, similar to the valve 16, and having ears 34 70 by means of which it is mounted on the pivot pin 35. The valve 33 has an extension 36 by means of which it may be actuated. In Fig. 6 the valve 33 is shown in position to close the extension 23 and thus shut off the 75 suction. When the valve is moved to the dotted line position 37, the opening 25 is closed and the suction acts through the casing 22 and the nozzle 27 drawing the dust-laden air through the screen 28. 80

Having thus described our invention, what we claim is:

1. In a vacuum cleaning tool, the combination of a casing having hollow connecting means adapted to be attached to vacuum-producing apparatus and to serve as a handle for the tool, an opening in said casing through which dust-laden air is drawn into the casing, a second opening in said casing through which the interior of the casing communicates with the external atmosphere, and a valve hinged in said casing so as to be capable of swinging from a position closing said second opening to a position closing 90 said connecting means, and said valve having a handle on the outside of said casing whereby the valve may be conveniently operated by the operator's thumb when the operator holds the tool by said connecting means. 100

2. In a vacuum cleaning tool, the combination of a tubular casing of substantially rectangular cross-section having a tubular extension on one side adapted to be attached to vacuum-producing apparatus, an opening in said casing through which dust-laden air is drawn into the casing, a second opening in said casing through which the interior of the casing communicates with the external atmosphere, and a valve hinged in said casing so as to be capable of swinging from a position closing said second opening to a position closing off said tubular extension from the interior of the casing, and said valve having a handle thereon projecting through said second opening and overlying said tubular extension. 110

3. In a vacuum cleaning tool, the combination of a casing having tubular connecting means adapted to be attached to vacuum-producing apparatus, said casing having an opening in its wall through which the interior of the casing communicates with the external atmosphere, a valve in said casing operable from the exterior and adapted to close said opening or said connecting means, a tubular extension through which dust-laden air is drawn into said casing, and a nozzle having a screened opening for co-operating with the articles to be cleaned, 120 125 130

said nozzle being detachably connected with said extension.

4. In a vacuum cleaning tool, the combination of a casing having tubular connecting means adapted to be attached to vacuum-producing apparatus, a screen through which dust-laden air is drawn into the casing, said casing having an opening in its wall through which the interior of the casing communicates with the external atmosphere, and a valve in said casing having a pivot so located that the valve is actuated by a current of air entering said opening to close off communication between said screen and said connecting means. 25

5. In a vacuum cleaning tool, the combination of a casing having tubular connecting means adapted to be attached to vacuum-producing apparatus, said casing having an opening through which dust-laden air is 30

drawn into the casing and a second opening through which air is adapted to flow into said casing, and a valve in said casing mounted on a pivot that is so located that the valve is adapted in one position to close said second opening and in another position to close off communication between the first-mentioned opening and said connecting means, said valve being movable from the position in which it closes said second opening to the position in which it closes off communication between the first-mentioned opening and said connecting means, by atmospheric pressure and a current of air flowing through said second opening. 35

In testimony whereof we affix our signatures.
